KNOB CONTROLLED COMBINATION LOCK

Mark A. Meuse, Yarmouth County,
Nova Scotia, CanadaApplication November 17, 1931
Serial No. 575,585

3 Claims. (Cl. 70—53)

This invention relates to a lock for safes, chests or other purposes, and it aims to provide a novel construction which will dispense with the use of a key and will provide for the inter-control of 5 preferably five knobs, the exact combination for which will be known alone to the authorized person and which combination it will be practically impossible to determine, if not known.

It is particularly aimed to provide a novel construction having a slidable member adapted to 10 connect operating means for the locking bar, through operation of certain of the knobs.

The more specific objects and advantages will 15 become apparent from a consideration of the description following taken in connection with accompanying drawings illustrating an operative embodiment.

In said drawings:—

Figure 1 is a side elevation of the lock, 20 Figure 2 is a longitudinal sectional view taken on the line 2—2 of Figure 1,

Figure 3 is a horizontal sectional view taken on a plane at a right angle to Figure 2,

Figure 4 is a view similar to Figure 3 showing 25 the parts shifted to release the locking plate so that it is free to be moved to unlocking position,

Figure 5 is a cross sectional view taken on the line 5—5 of Figure 3,

Figure 6 is a cross sectional view taken on the 30 line 6—6 of Figure 3,

Figure 7 is a cross sectional view taken on the line 7—7 of Figure 3,

Figure 8 is a cross sectional view taken on the line 8—8 of Figure 3,

Figure 9 is a detail section taken on the line 35 9—9 of Figure 2,

Figure 10 is a cross section taken on the line 10—10 of Figure 2,

Figure 11 is an enlarged cross section taken on 40 the line 11—11 of Figure 2, and

Figure 12 is an enlarged cross section taken on the line 12—12 of Figure 2.

Referring specifically to the drawings, the invention is applicable to a lock used for any desired purpose and hence the particular lock illustrated is to be considered by way of illustration only. Such lock embodies a suitable casing at 10, the specific details of which form no part of the invention. Mounted for longitudinal sliding 45 movement in the casing 10 is a locking plate 11. Such plate is limited in its movement by cross members 12 and its ends are disposed in the grooves of mounting elements 13, secured as shown at 14 to the casing 10. Said plate 11 has 50 one or more recesses 15 therein in line with open-

ings 16 in the casing 10, through which keeper members 17 may extend from a plate 18 attached to the door, cover or the like to be locked. The plate 11 has lugs 19 thereon which extend into openings of the keepers 17 in order to effect the locking of the plate 18. The sliding movement of the locking plate 11, under control of the combination means to be described, enables the plate 11 to move and accordingly move the lugs 19 out of engagement with the keepers 17 whereby the latter are released.

The lock plate 11 has a recess therethrough in which rack teeth 20 are provided. The rack teeth are in mesh with teeth 21 of a ring or annulus 22, one side of which is flat as at 23 where it is engaged by a leaf spring 24 in order to maintain the same in a predetermined position, to facilitate locking and unlocking movement.

Within the casing 10 below the lock plate is a base plate 25, rigidly secured to the casing. Suitably journaled in the base plate 25 and adjacent portions of the casing are spindles 26, 27, 28, 29 and 30. Each of said spindles exteriorly of the casing has a knob 31 fixed thereon and also a pointer 32 which coacts with a dial 33 arranged about the same.

The previously mentioned annulus 22 is journaled on the spindle 27 and thus the latter is normally turnable or rotatable independently of the annulus. A slide 33^a, upheld by a leaf spring 34, passes through a diametric slot 35 in the spindle 27. Slide 33^a has a lug 36, normally spaced from a slot or notch 37 in the annulus 22, and which slide is adapted to be moved so as to dispose the lug 36 in the slot 37 to thereby couple the annulus and spindle 27, to the end that operation of the latter will cause the teeth 21 to coact with teeth 20 and thereby slide the lock plate 11 to unlocking position.

The improved lock has means coacting with the various spindles 26, 28, 29 and 30, to render it practically impossible to actuate the slide 33^a under normal conditions, that is unless actuated by someone knowing the combination necessary for successful operation of the spindles. To this end, a series of auxiliary slides 38, 39, 40 and 41, are mounted in elements 42 rigid with the base plate 25. Said slides are normally retracted or urged away from the main slide 33^a by expansive springs 43.

On the spindles 28 and 29, are disks 41^a having upstanding lugs 42^a, in which slides 43^a are mounted, the same having enlarged openings 44 through which the spindles 28 and 29 pass. Expansive coil springs 45, are associated with the 110

slides 43^a to maintain them in normal position. It will thus be realized that the successful operation of the device depends upon alinement of the various slides 39, 43^a, 40, and 41, with the 5 main slide 33^a. With such slides thus alined, actuation of spindle 30 will slide them as a unit in view of the provision of a cam 46 on the spindle 30 abutting and moving the slide 41. This is possible only when the slide 38 is retracted since this 10 slide normally engages the main slide 33^a and prevents movement thereof. A cam 47 on the spindle 26, normally maintains the slide 38 in contact with the main slide 33^a and operation of the cam 47 so displaces it that the spring 43 moves the 15 slide 38 to a position affording clearance for sliding of the main slide 33^a. Even when slide 38 is moved to provide clearance for slide 33^a, this latter element cannot move until lug 36 on slide 33^a is alined with notch 37 in annulus 22.

20 Leaf springs 48 may engage various spindles 26, 27, 28, 29 and 30, to maintain the same in positions to which they are adjusted, to thus in effect serve as friction brakes.

Various changes may be resorted to provided 25 they fall within the spirit and scope of the invention.

I claim, as my invention:

1. A lock of the class described having a locking plate, an operating element in geared relation therewith having a slot, an operating spindle normally movable independently of said element, a slide carried by the spindle, a lug on said slide, a slide normally preventing the first slide from

moving its lug into said slot, and controlled means operable to move said lug into said slot after movement of the second slide, whereby the spindle and operating element will be coupled for unitary actuation.

2. A lock of the class described having a locking plate, an operating element therefor, an operating spindle normally movable independently of said element, a slide carried by the spindle and adapted for coupling engagement with said operating element, a slide normally preventing the first slide from moving into coupling engagement with said element, and controlled means operable to move said first mentioned slide into coupling engagement with the operating element after movement of the second mentioned slide, whereby the spindle and operating element will be coupled for unitary actuation.

3. A lock of the class described having a locking plate, an operating element, means whereby actuation of the element will move the plate, an operating spindle normally movable independently of said element, a slide carried by the spindle, a slide normally preventing the first slide from moving into coupling engagement with said element, and a series of control slides normally preventing clutch engagement of the first mentioned slide with the operating element, and operable to effect said engagement, whereby the spindle and operating element will be coupled for unitary actuation after actuation of the second mentioned slide.
